Application May 21, 1953, Serial No. 356,518

Claims priority, application Germany May 24, 1952

6 Claims. (Cl. 73—81)

This invention relates to new and useful improvements in hardness-testing devices.

The hardness of materials can be ascertained by measuring the size indentation produced therein by means of a weighted indenter which usually consists of a diamond point. In order to avoid errors in measurement, it is important that during the formation of the indentation, the diamond point shall be lowered precisely linearly as it penetrates into the material to be tested. Devices are known in which the indenter diamond is mounted on a guide lever whose fulcrum is located at exactly the same level as the diamond point. A tangent drawn at this point to the arc of the path described by the diamond is perpendicular to the specimen tested. Inasmuch as the diamond point penetrates into the material but slightly, its movement may be considered effectively linear.

Careful investigation has revealed that measurements thus produced lacked the desired degree of accuracy. After extensive research and experimentation, the cause of the error was discovered and a novel construction devised which obviates the shortcomings of the known devices. It was found that in these devices, the weights applied cause a slight bending of the guide lever and the guide lever support. Subsequently, when the diamond point, in its downward movement, engages the test specimen and cuts into it, the bending stress is relieved, causing a straightening of the guide lever. As a result, the diamond point is subjected to a component of lateral or horizontal motion, whereby the indentation produced is horizontally enlarged and the measurement falsified. This error is particularly noticeable in micro-hardness testing, when small loads are used.

An object of the invention is to eliminate this source of error and provide a simple, yet highly accurate and reliable hardness-testing device.

In brief, the present invention provides separate and independent supporting means for the indenter-carrying guide lever, on the one hand, and the load applying structure on the other hand. In one form of construction, the burden of the load is transferred to the indenter and the test specimen by electrically heating a bimetallic arm. The transfer is thereby caused to be smooth and continuous. In an other embodiment of the invention, an electric current is passed through a wire which initially supports the burden of the weights. Linear expansion of the wire when heated by the electric current causes the burden of the weights to be applied to the indenter and test specimen.

According to a preferred form of construction, the guide lever and weight or load applying element are separately supported for rotation about vertical axes and may be swung outwardly, away from the base plate on which they are mounted, so that large specimens, for instance machine parts, may readily be tested.

With these and other objects in view, as will become more apparent from the following specification, several

embodiments of the invention are illustrated, by way of example, in the accompanying drawings in which:

Figure 1 is an elevational view showing a testing device in accordance with the invention and which employs a bimetallic strip for applying the load to the indenter and specimen.

Figure 2 illustrates details of a modified form of the invention in which the linear expansion of an electrically heated wire is employed for loading the indenter, the device of Figure 2 being otherwise similar to Figure 1.

Figure 3 is a bottom plan view of the guide lever showing its point and knife-edge bearing members.

As shown in Fig. 1, a base plate 1 carries two separate supports or uprights 2, 3 and a specimen table 5. Reference numeral 4 designates the specimen to be tested. A supporting arm 6 is rotatable on sleeve 6a which is vertically adjustable on upright 2 by means of a rack and pinion mechanism 2a. Sleeve 6a may be locked in position by locking or stop lever 2b which is provided with an eccentrically mounted cam element 2c. Supporting arm 6 carries the test arm or guide lever 7 having point and knife-edge bearings 8, 8', respectively; (see Fig. 3). Guide lever 7 is provided with a horizontal sliding surface 9 which rests on a cooperating anti-friction element 10 such as a ball or roller, the latter being disposed in a suitable recess or otherwise retained in position by conventional means. The indentation forming element or indenter 11, which may be provided with a diamond point, for instance, is mounted on guide lever 7. Weights 12 are suspended, for instance, by means of a wire or thread 12a from the free end portion of a bimetallic strip 24. One end of the strip 24 is fixed in a supporting arm 30 which is preferably of adjustable length, conventional means (not shown) being provided for this purpose. Supporting arm 30, like the arm 6 previously described, is rotatable in a horizontal plane on a sleeve 3a. The sleeve 3a is vertically adjustable on upright 3 by means of a rack and pinion mechanism 3b so that it raised or lowered at will. The weights 12 rest on the guide lever 40 7 directly above the indenter 11.

In order to be able to test large pieces of machinery which cannot be accommodated on table 5, arm 6 is constructed of sufficient length and mounted rotatably on upright 2 so that it may be swung out horizontally beyond the base plate in order to place indenter 11 in the desired position above the machine part to be tested. Supporting arm 30, which carries the bimetallic strip 24, may likewise be swung about and in order to position the weights directly above indenter 11, arm 30 being of adjustable length inwardly or outwardly with respect to upright 3. It will be clear that instead of making arm 6 and the weight supporting arm 30 rotatable on uprights 2, 3, the latter may be rotatably mounted on the base 1. To provide for adjustment of the lengths of the arms 6 and 30, a telescopic form of construction may be employed.

An electrical resistance element 24a is disposed on the bimetallic strip 24. The resistance element 24a is connected in an energizing circuit including a source of electrical energy indicated as a battery 22 and a control switch 23.

The operation of the testing device is as follows: Specimen 4 is placed on the table 5. The arm 6 is then lowered by means of rack and pinion mechanism 2a until the indenter 11 engages the upper surface of the specimen 4 and the horizontal surface 9 is clear of the ball or roller 10. Rack and pinion mechanism 3b is then manipulated so that with the switch 23 open, the entire burden of the weights 12 is carried by the bimetallic strip 24 so that the load on the indenter 11 and specimen 4 is substantially zero, a slight clearance between the point of the indenter and the specimen being permissible.

Switch 23 is then closed and the resistance element 24a heats the bimetallic strip 24 causing its free end portion to move downwardly. This, in turn, removes the support for the weights 12 so that their entire burden is transferred to the indenter 11 and the specimen 4. Flexure of the upright 3 as the burden of the weights 12 is relieved produces no flexure of the other upright 2 and hence no tendency to cause horizontal movement of the indenter 11 as it penetrates into the specimen 4. The center of gravity of the weights 12 being directly above the point of the indenter 11, there is no force present which might tend to produce undesirable horizontal movement of the indenter 11 as it penetrates into the specimen 4. The pivots 8, 8' and the point of the indenter 11 lie in a common substantially horizontal plane so that the short path of downward movement of the indenter is further constrained by the guide lever 7 to be substantially precisely vertical, thus avoiding any error-producing horizontal enlargements of the indentation formed in the specimen 4 by the point of the indenter 11.

In the modified form of the invention shown in Fig. 2, the bimetallic strip 24 and heating resistor 24a have been replaced by a vertical wire 21. The construction is otherwise the same as that shown in Fig. 1. When the switch 24 is closed, the wire 21 becomes heated and expands longitudinally so that the burden of the weights 12 is gradually transferred from the arm 30 and wire 21 to the indenter 11 and specimen 4. The method of operation is similar in all respects to that described above in connection with Fig. 1.

Various changes and modifications may be made without departing from the spirit and scope of the present invention and it is intended that such obvious changes and modifications be embraced by the annexed claims.

We claim:

1. A hardness testing device producing indentations for microscopic evaluation, comprising: a first supporting means, a guide lever pivoted to the latter, indenter means carried by the free end portion of said guide lever, at least one weight supported on said free end portion, second independent supporting means, a resistance wire connected to said second supporting means and to the free end portion of said guide lever, to support the latter in suspended relationship with respect to said second supporting means, means for impressing an electric current on said resistance wire to heat the same and produce an elongation thereof, to lower the end portion of said guide lever whereby said indenter, when it is lowered onto a test specimen and is unsupported by said resistance wire, applies the burden of said weights to the test specimen and produces a test indentation therein solely by the burden of said weight and free from any lateral deformations which would otherwise be caused by the production of a bending moment in said guide lever or said first supporting means.

2. A hardness testing device comprising: a first supporting means, a guide lever pivoted to the latter, indenter means carried by the free end portion of said guide lever, at least one weight supported on said free end portion, second supporting means, said second supporting means being independent of said first supporting means whereby a change in the loading of said second supporting means produces no stresses in said first supporting means or said guide lever, a bi-metallic element carried by the latter, connecting means secured to said bi-metallic element and the free end portion of said guide lever to support the same in suspended relationship with respect to said bi-metallic element, controllable heating means associated with said bi-metallic element to heat the latter and cause the same to bend, to lower the suspended end

portion of said guide lever, whereby said indenter, when it is lowered onto a test specimen and is unsupported by said connecting means, applies the burden of said weights to the test specimen and produces an indentation therein, 5 said indentation being formed solely by the burden of said weights, the independence of said second supporting means from said first supporting means preventing the formation of any lateral deformations in said indentation.

3. A device for testing the hardness of a specimen by producing indentations for microscopic evaluation, comprising supporting means, an electrically actuated element carried by said supporting means, weighted indentation forming means carried by said electrically actuated element and normally maintained above said specimen, and an electrical control circuit connected to said electrically actuated element for actuating the same, actuation of said electrically actuated element serving to lower said weighted indentation forming means on to said specimen.

20 4. A device for testing the hardness of a specimen by producing an indentation therein for subsequent microscopic evaluation, comprising supporting means, an electrically actuatable element supported by said supporting means, a pivotally mounted guide lever carried at its free end by said element, indentation forming means at said free end of said guide lever and normally maintained above said specimen, weight means on said free end of said guide lever, said electrically actuatable element carrying the burden of said weight means, and an electrical control circuit connected to said electrically actuatable element for actuating the same, actuation of said element serving to lower said indentation forming means into contact with said specimen, thereby transferring the burden of said weight means on said guide lever to indentation 30 forming means and said specimen.

5. A device according to claim 4, in which said electrically actuatable element comprises a bimetallic strip and electrical heating means disposed in thermally conductive relationship with respect to said strip, said control circuit being connected to said heating means to cause warping of said strip.

6. A device according to claim 6, in which said electrically actuatable element comprises an electrical resistance wire which carries the burden of said weight means, said wire being elongated upon passage of current therethrough, said control circuit being connected to said resistance wire.
